UNITED STATES PATENT OFFICE

ROBERT H. WAGER, OF JERSEY CITY, NEW JERSEY

LATHER-FORMING DEVICE

Application filed March 10, 1927, Serial No. 174,320. Renewed December 12, 1929.

This invention relates to new and useful improvements in lather forming devices for shaving purposes, of the same general type disclosed in my U. S. Patents 1,554,146; 1,554,147 and 1,554,148 of September 15, 1925. In the patented structures, a liquid container is disclosed having a soap cake supporting platform and means thereunder for discharging air or other desired gas into the liquid, to agitate the latter and form soap bubbles. A bubble-condensing unit, for converting the bubbles to a thick creamy lather, is clamped against the upper end of the container wall by a cap which is provided with a lather discharge spout.

It is the aim of the present invention to generally improve and simplify the patented constructions, producing a better device at less cost, and in carrying out this end, further objects are:—to provide improved means for supporting the soap cake with its lower side exposed to the agitated liquid; to provide improved means insuring that the liquid shall be agitated under the cake as well as around the same; to make novel provision preventing any of the soapy liquid from reaching a check valve within the gas inlet passage of the container and causing this valve to lodge against its seat; to produce an improved bubble-converting unit all of whose bubble-condensing screens are encased and hence protected; to provide a construction in which the same screening effect as that previously produced by relatively large screens, is attained with the use of less screening material; to provide a bubble-converting unit in which previously unoccupied space is utilized to contain additional screens; to provide a bubble-converting unit which is permanently sealed at the factory and hence cannot be taken apart and tampered with by the purchaser; and to provide a new and improved construction and relation of parts for retaining the bubble-converting unit in place and permitting the use of a single gasket to establish a fluid-tight seal between the container and its cap.

With the foregoing and minor objects in view, the invention resides in the novel subject matter hereinafter described and claimed,

the description being supplemented by the accompanying drawings.

Fig. 1 is a side elevation.

Fig. 2 is an enlarged vertical sectional view.

Fig. 3 is a side elevation showing the lather discharge cap disconnected from the container, and illustrating the filling plug removed from the latter.

Figs. 4, 5, 6, 7 and 8 are horizontal sectional views on the correspondingly numbered lines 60 of Fig. 2.

Fig. 9 is a vertical sectional view through portions of the bubble-converting means in disassembled relation.

Fig. 10 is a sectional view similar to a portion of Fig. 2 but illustrating a different form of construction.

Fig. 11 is a detail sectional view through a portion of the cap, showing a different construction from that illustrated in the other views.

Fig. 12 is a detail vertical sectional view showing a different manner of supporting the bubble-converting unit.

Fig. 13 is a sectional perspective view, illustrating a modified ring construction which may be used if desired for securing certain screens in place.

In the drawings above briefly described, preferred features of construction have been illustrated and while such features will be hereinafter specifically described, it is to be understood that within the scope of the invention as claimed, numerous variations may be made.

12 denotes a liquid container having a filling opening 13 which is so located as to prevent filling of the container beyond a predetermined level, this level being indicated at 14 in Fig. 2. A suitable plug 15 having a gasket 16, is provided for the opening 13, and said plug is preferably formed with integral lugs (not shown) engageable with bayonet slots or the equivalent 17, permitting the plug to be quickly and easily secured in place or removed, as occasion may demand.

The lower portion of the container 12 is formed with a gas inlet passage 18 which is preferably connected with a hand bulb 19, the inner end of said passage being upwardly

directed as indicated at 20. This upwardly turned end of the gas inlet passage 18 communicates with the lower end of a vertical tube 21 (most views) or 21^a (in the modification of Fig. 10). The container bottom is provided with a conical formation at its upper side and this formation may either be integral with said bottom as denoted at 22 in Fig. 2, or it may be separate from the bottom, as indicated at 22^a in Fig. 10. When the former construction is employed, the tube 21 may be threaded into the upper end of the formation 22, as indicated at 23, but when the construction of Fig. 10 is employed, the lower end of the tube 21^a is threaded at 23^a into the container bottom under the conical formation 22^a, and the latter is formed with an opening 24 receiving said tube. In either instance, the tube will receive gas from the upturned end 20 of the passage 18, and it will be observed from Fig. 2 that this tube is provided with gas discharge openings 25 above the liquid level 14. An upwardly opening check valve 26 is disposed within this tube and acts in conjunction with the usual inlet valve of the bulb 19, and it will be observed that none of the soapy liquid from the container 12 can reach the valve 26, due to the fact that the openings 25 are disposed above the liquid level 14. Thus, there is no danger of any soap collecting upon the valve and its seat and causing the former to lodge against the latter.

A vertical sleeve 27, surrounds the tube 21, a spaced relation therewith, and is provided at its lower end with an outstanding flange 28 of conical formation. This flange is spaced above the conical formation 22 or 22^a and its peripheral edge terminates in spaced relation with the container wall to permit the discharge of gas into the liquid, said gas being received by the sleeve 27 from the openings 25 and conducted downwardly by this sleeve into the space 30 between the two conical formations 28-22 or 28-22^a, as the case may be.

One of the conical formations (28 or 22-22^a) is provided with means for whirling the gas passing through the space 30 and directing such gas circumferentially of the container wall as it discharges, so as to produce effective whirling and agitation of the liquid in the container 12. In the present showing, the means just referred to, are in the form of curved ribs 31 upon the upper surface of the conical formation 22-22^a, said ribs being spaced apart and hence providing curved passages whose inner and outer ends are open. The flange 28, which is rigidly attached to the lower end of the sleeve 27 in any preferred manner, rests solidly upon the ribs 31 and is held in this position by the enlarged head 33 of a screw 34, the latter being threaded into the upper end of the tube 31. The head 33 is preferably shouldered

at 35 to fit partly within the upper end of the sleeve 27 to hold the latter centered with regard to the tube 21.

36 denotes an annular soap cake whose central opening 37 receives the sleeve 27, said sleeve and associated parts thus constituting a post for holding the soap cake with its periphery spaced from the side wall of the container 12. Due to the formation of the flange 28, upon which the soap cake 35 rests, only the inner lower corner 38 of the soap cake will engage said flange, and hence, an annular space 39 is left between the flange and the soap cake, in which the agitated water may act against the lower side of said cake. 80

Preferably, the soap cake 36 is of such thickness that its upper portion is disposed above the liquid level 14 and its lower portion below said liquid level, until the cake has washed away to quite an extent, but as the lower side of said cake is worn away by contact with the agitated liquid, the cake gradually lowers by gravity, so that it is at all times supported by the flange 28. 85

The features of constructions so far described, are instrumental in producing soap bubbles, and for the purpose of converting these bubbles into a thick creamy lather, suitable for shaving, I provide a bubble-converting unit 41, the lower portion of said unit fitting into the open upper end of the container 12. This unit is preferably supported directly upon the soap-cake-positioning-post and is provided with a boss 40 resting on the screw head 33 thereof. Hence, the soap-cake-positioning-post serves to effectively support the unit 41, without any necessity of providing the latter with an outstanding rib or the like to engage the upper edge of the container wall. Moreover, contact of unit 41 with the screw head 33, prevents the screw 34, holding sections of the post together, from being accidentally loosened or removed. 100 115

If desired, the unit 41 may be supported by ribs, such as 40^a of Fig. 12, instead of being supported by the soap-cake-positioning-post, said ribs being formed on the container wall. 110

The unit 41 is analogous to the bubble-converting unit shown in Fig. 2 of U. S. Patent 1,554,148, but certain distinct improvements have been made. This unit embodies a central plate 42 provided on each of its upper and lower sides, with a continuous annular flange 43, the peripheral surfaces of said flanges and plate being preferably flush so as to produce a strictly cylindrical formation for the unit 41. Plate 42 is formed with a central opening 44, and between this opening and the flanges 43, each of the upper and lower sides of said plate are formed with a pair of continuous channels 45, the channels at each side of the plate being in communication at spaced points, by means of appropriate ports 46. 120 125

Fitting within the flanges 43 and positioned 130

above and below the plate 42, are two additional plates 47 and 48 having channels 49 which are opposed to the channels 45, the innermost of these channels being in communication with the upper and lower ends of the opening 44 and being in communication with the next adjacent channels, by means of radial ports 50. The outermost channel of the plate 48 (the lowermost) is formed 10 with a plurality of inlet openings 51, and the corresponding channel of the upper plate 47 is provided with outlet openings 52. Annular screens 53 are provided for these openings, said screens being disposed within the 15 channels with which said openings communicate, and being held in proper position across said openings by rings 54 (Figs. 2 and 6) or 54^a (Fig. 13) or rings of other desired form, said rings having frictional engagement with the opposed side walls of the channels. The 20 rings 54 are flat and are formed with appropriate openings 55 which are preferably elongated as shown in Fig. 6, and if desired, these rings may be of a thickness corresponding to 25 the depth of the channels 49. The ring 54^a is of zig-zag form and needs no openings such as 55. In Fig. 2 of Patent 1,544,148, openings corresponding to the openings 51 and 52 are disclosed, provided with no screens, but in 30 the manufacture of the device, screens were placed over the entire top and bottom of the bubble-converting unit, to screen these openings. The screens were secured at their centers and peripheries and while they attained 35 good results, this construction required a great deal more of the screening material, than the present construction, in which the small annular screens 53 are disposed within certain of the channels 49.

40 In the patent last referred to (Fig. 2), a central opening corresponding to the opening 44, was left unoccupied, but in the present device, I utilize this opening to retain alternate screens 56 and spacers 57.

45 Between the central plate 42 and the plates 47-48, screens 58 are provided, extending across the numerous channels of the plates, as in Patent 1,544,148. The relation of parts is such that the portions of these screens, at 50 the endmost of the spacers 57, are backed up by portions of the plates 47 and 48, relieving said screens of the strain of holding the spacers 57 and screens 56, against shifting.

55 I prefer to permanently secure the plates 47-48 within the flanges 43, so that the unit 41 cannot be disassembled and tampered with by the purchaser. To accomplish this, I prefer to bevel the outer corners of these plates, as indicated at 59 and to provide fins 60 integral with the flanges 43 and extending continuously around the inner corners of the latter. Prior to assembly, these fins stand as seen in Fig. 9, but after the entire unit 41 has been assembled, the fins 60 are turned 60 inwardly as shown in Fig. 2, said fins then

contacting with the bevels 59 and being flush with the edges of the flanges 43 and with the outer surfaces of the plates 47-48.

The upper portion of the bubble-converting unit 41 projects above the side wall of 70 the container 12, and fitting over this upwardly projecting portion of said unit and the upper portion of the container 12, is a cap 61 having a lather discharge spout 62. The side wall or depending skirt portion of this 75 cap may have its upper and lower portions formed of separate sections 63 and 64, engaged as shown in Fig. 2, or the upper and lower portions may be integrally connected with each other as in Fig. 11, in which view 80 the portions in question are denoted at 63^a and 64^a. In either instance, the lower portion of the cap wall is outwardly offset from the upper portion, providing a downwardly facing shoulder 65 (Fig. 2) or 65^a (Fig. 11). 85 This shoulder is spaced directly above the upper edge of the container side wall, and a gasket 66 is interposed between said shoulder and edge to establish a fluid-tight connection between the cap 61 and the container 12, when 90 the former is downwardly drawn by means yet to be described. When this cap moves downwardly to the maximum, an internal, downwardly facing shoulder 67 with which it is provided, abuts the upper side of the 95 unit 41 and thus holds the latter tightly down against the soap-cake-positioning-post. During this downward movement of the cap, compression of the gasket 66 of course takes place 100 to insure a tight joint, and the shoulder 67 does not abut the unit 41, until maximum compression of said gasket has taken place.

105 While any desired means may be employed to connect the cap 61 with the container 12 and to draw said cap downwardly for the purpose above set forth, I prefer to provide the container wall with outwardly projecting, inclined lugs 68 (Fig. 3), said lugs being receivable in bayonet slots 69 in the lower portion of the cap wall. Both the lugs 68 and the co-acting portions of the slots 69 are inclined, so that upon rotation of either the lower section 64 of the cap wall or the entire cap, according to the construction followed, the cap and container will be tightly 110 connected and the former will be drawn downwardly upon the latter. This lug and slot connection also permits quick and easy demounting of the cap 61 from the container 115 120 125 130 135 140 145 150 155 160 165 170 175 180 185 190 195 200 205 210 215 220 225 230 235 cake 36, and such liquid is effectively agitated in the space 39 to receive the necessary quantity of soap from the lower surface of the soap cake. The soap bubbles generated by this agitation of the liquid in the presence of the soap cake, accumulate in the upper portion of said container, above the liquid level, and are forced by the accumulating gas pressure through the bubble-converting unit 41, said bubbles traveling repeatedly through the screening means, so that by the time they leave the outlet openings 52 of said unit, they have reached a thick creamy consistency suitable for shaving purposes. This shaving cream is discharged through the outlet 62 and is preferably applied to the face with the hand, thus dispensing with the use of the usual shaving brush.

On account of the advantages existing for the details of construction herein disclosed, they may well be followed, but as above stated, numerous variations may be made within the scope of the invention as claimed.

I claim:—

1. In a lather forming device, a container in which soap bubbles are formed and from which they are discharged by gas under pressure, said container having an open upper end, a bubble-converting unit having its lower portion received within the open upper end of the container, means within said container for supporting said unit, a lather-discharge cap receiving the upper portions of said unit and said container wall and formed with an internal downwardly facing shoulder spaced above the upper edge of said wall, a gasket between said shoulder and edge, and co-acting means on the cap and container wall for effecting downward movement of the cap to compress the gasket, establishing a fluid-tight connection between cap and container.

2. A structure as specified in claim 1; said cap having a portion which abuts said unit and holds it tightly down against its supporting means, upon maximum compression of the gasket.

3. In a lather forming device, a container for a saponaceous liquid, said container having an open upper end, means for injecting a gas under pressure into the liquid containing portion of said container to agitate the saponaceous liquid and form soap bubbles, a bubble-converting unit fitting into the open upper end of said container and disposed above the normal liquid level, a lather-discharge cap over said unit and connected with the container, and a post in the container supporting the aforesaid unit, a portion of said post being disposed in the liquid containing portion of the container to hold a soap cake therein.

4. A structure as specified in claim 3; said post having a removable portion at its upper end held against accidental removal by contact with said bubble-converting unit.

5. A structure as specified in claim 3; said post being of sectional formation and having one of its sections secured in place by a screw at the upper end of the post, said screw being held against accidental removal by contact with said bubble-condensing unit.

6. In a bubble-producing means for a lather forming device, a container for a saponaceous liquid, a gas inlet tube rising rigidly into said container and having a gas outlet above the normal liquid level, a soap cake positioning sleeve surrounding and spaced from said tube, providing a chamber to receive the gas from said gas outlet, said sleeve having a closed upper end, provision being made to permit discharge of gas into the liquid from the lower end of said sleeve, and soap cake supporting means carried by said sleeve.

7. In a bubble-producing means for a lather forming device, a container for a saponaceous liquid, a gas inlet tube rising rigidly into said container and having a gas outlet above the normal liquid level, and a soap cake positioning sleeve surrounding and spaced from said tube, providing a chamber to receive the gas from said gas outlet, said sleeve having a closed upper end and an open lower end, the latter being provided with an outstanding annular soap cake supporting flange which is spaced above the container bottom and is spaced also from the container wall, permitting discharge of gas into the liquid.

8. A structure as specified in claim 7; said flange being of substantially conical formation to contact at its smaller upper end only with the soap cake.

9. A structure as specified in claim 7; said flange being of substantially conical formation and being adapted to support an annular soap cake, and a complementary conical formation at the upper side of the container bottom spaced a slight distance below the flange to provide for the discharge of the gas, one of said conical formations having pitched ribs for whirling the gas to effect through agitation of the liquid.

10. In a bubble-producing means for a lather forming device, a liquid container having a substantially conical formation at the upper side of its bottom, a rigid gas inlet tube disposed at the upper end of said substantially conical formation and having a gas outlet above the liquid level of the container, the upper side of said substantially conical formation having pitched ribs extending to its periphery from the tube, a gas conducting sleeve surrounding and spaced from said tube, the lower end of said sleeve having a substantially conical soap-cake supporting flange resting on said ribs and terminating in spaced relation with the container wall to permit discharge of gas from the spaces between said ribs, and a screw threaded into

- the upper end of the tube, said screw being provided with a head which closes the upper end of the sleeve and holds the latter and its flange against upward movement.
- 5 11. In a bubble-producing means for a lather forming device, a liquid container having a substantially conical soap cake support for contact at its upper smaller end only with the soap cake, means for holding the 10 soap cake against tilting on the support and for maintaining spaced relation between the cake and the container wall, and means whereby the liquid may be agitated around and under the soap cake, said container 15 having an outlet above its normal liquid level to discharge generated bubbles and being otherwise closed against discharge of liquid when in normal position.
12. In a bubble-producing means for a 20 lather forming device, a liquid container having a substantially conical soap cake support for contact at its upper smaller end only with the soap cake, a post rising to a point above the upper end of said support for reception in an opening of the soap cake to hold the latter in spaced relation with the container wall, and means whereby the liquid may be agitated around and under the soap cake, said container having an outlet above 25 its normal liquid level to discharge generated bubbles and being otherwise closed against discharge of liquid when in normal position.
13. In a bubble-producing means for a lather forming device, a liquid container 30 having a substantially conical soap cake support for contact at its upper smaller end only with the soap cake, means for holding the soap cake against tilting on the support and for maintaining spaced relation between the 35 cake and the container wall, and means for discharging gas at the peripheral edge of said support toward the container wall.
14. In a bubble-producing means for a lather forming device, a liquid container 40 having a substantially conical soap cake support for contact at its upper smaller end only with the soap cake, means for holding the soap cake against tilting on the support and for maintaining spaced relation between the 45 cake and the container wall, and means for discharging gas at the peripheral edge of the support and directing it circumferentially of the container wall to whirl the liquid about and under the soap cake.
- 50 15. In a bubble-producing means for a lather forming device, a liquid container provided with a bubble outlet above its normal liquid level and otherwise closed against escape of liquid, a soap cake positioning post disposed within said container and adapted 55 for passage centrally through an annular soap cake, said post having gas-conducting means discharging below the liquid level of the container, soap cake supporting means at 60 the periphery of the post and spaced above 65 the container bottom, and means for injecting a gas into said gas-conducting means.
16. In a bubble-converting means for a lather forming device, a member having a bubble-conducting channel and bubble-conducting openings communicating therewith, a bubble-condensing screen in the channel extending across said opening, and a ring secured in said channel, the screen being tightly held between said ring and a wall of the 70 channel.
17. A bubble-converting unit for a lather forming device, comprising a central plate having an opening from one side to the other and provided with a continuous flange at each of said sides, the latter having continuous channels between the opening and flanges, two additional plates fitting within said flanges and having channels opposed to those of the central plate; one of said additional plates having an inlet opening into one of its channels, the other of said additional plates being formed with an outlet opening from one of its channels, and the three plates having ports from one channel to another; bubble-condensing screens clamped between the central plate and the additional plates, spaced bubble-condensing screens in the first named opening, and bubble-condensing screens across said inlet and outlet openings mounted in the channels with which these openings communicate.
18. In a bubble-producing means for a lather forming device, a liquid container provided with a bubble outlet above its normal liquid level and otherwise closed against escape of liquid, a post disposed centrally within said liquid container and adapted to be surrounded by bubble-forming soap, said post having gas-conducting means discharging below the liquid level of the container, and means for injecting a gas into said gas-conducting means.
19. In a bubble-producing means for a lather forming device, a liquid container provided with a bubble outlet above its normal liquid level and otherwise closed against escape of liquid, a tube rising rigidly into said container and having a gas outlet above the normal liquid level, a sleeve removably surrounding said tube and adapted to be surrounded by bubble-forming soap, said sleeve being spaced from the tube to conduct the gas from said tube downwardly, the lower end of said sleeve being flared and open and adapted to discharge the gas into the liquid, and means for injecting a gas into said tube.
20. In a lather forming device, a liquid container provided with a bubble outlet above its normal liquid level and otherwise closed against escape of liquid, bubble-condensing means into which said outlet discharges, a tube rising rigidly into said container and having a gas outlet at its upper end disposed above the normal liquid level, said tube being 100 105 110 115 120 125 130

adapted for reception within a soap-carrying sleeve, and means for discharging gas into said tube, the upper portion of the container being removable to allow insertion and removal of the soap-carrying sleeve.

5 21. In a bubble-producing means for a lather forming device, an elongated soap-carrying sleeve adapted to receive a gas-discharging tube, said sleeve having a closed upper end and having a flared open lower end.

10 In testimony whereof I have hereunto affixed my signature.

ROBERT H. WAGER.
